US00D350782S

United States Patent [19]

Barr

[11] Patent Number: Des. 350,782

[45] Date of Patent: ** Sep. 20, 1994

[54] **CONTROLLER FOR VIDEO GAME MACHINE**

[75] Inventor: **Lance Barr**, Renton, Wash.

[73] Assignee: **Nintendo of America Inc.**, Redmond, Wash.

[**] Term: **14 Years**

[21] Appl. No.: **8,632**

[22] Filed: **May 24, 1993**

[52] U.S. Cl. **D21/48**

[58] Field of Search ..... 273/148 B, 433-438, 273/DIG. 28; D21/13, 48; D14/125, 126, 114

[57] **CLAIM**

The ornamental design for a controller for video game machine, as shown and described.

DESCRIPTION

FIG. 1 is a front, top and right side perspective view of a controller for video game machine showing my new design;

FIG. 2 is a rear, bottom and left side perspective view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof;

FIG. 8 is a bottom view thereof;

FIG. 9 is a front, top and right side perspective view of a second embodiment of a controller for video game machine illustrated in FIG. 1;

FIG. 10 is a rear, bottom and left side perspective view of the second embodiment;

FIG. 11 is a front elevational view of the second embodiment;

FIG. 12 is a rear elevational view of the second embodiment;

FIG. 13 is a right side elevational view of the second embodiment;

FIG. 14 is a left side elevational view of the second embodiment;

FIG. 15 is a top plan view of the second embodiment; and,

FIG. 16 is a bottom view of the second embodiment.
